V. J. AULT.
COMBINATION TOILET ARTICLE.
APPLICATION FILED JUNE 28, 1920.

Patented Jan. 25, 1921.

UNITED STATES PATENT OFFICE.

VAN JENNINGS AULT, OF HANCOCK, MINNESOTA.

COMBINATION TOILET ARTICLE.

1,366,762.

Specification of Letters Patent. Patented Jan. 25, 1921.

Application filed June 28, 1920. Serial No. 392,342.

To all whom it may concern:

Be it known that I, VAN JENNINGS AULT, a citizen of the United States, residing at Hancock, in the county of Stevens and State of Minnesota, have invented a new and useful Combination Toilet Article, of which the following is a specification.

This invention relates generally to improvements in toilet articles of that type embodying facilities for accomplishing a variety of purposes.

The principal object of the invention is to provide a combination toilet article having a two-part body or casing forming a container adapted to receive scissors, hairpins and the like, and constructed to resemble in configuration and serve in a capacity similar to the conventional type of back for hair brushes.

Another object of the invention is to provide a combination toilet article wherein a comb, brush and mirror are mounted upon the aforesaid casing in such a manner as to be readily adaptable for use in their respective capacities without inconvenience to the user.

A further object of the invention is to so construct the back or casing of the toilet article that the sections of which it is formed will afford when closed a compact object which presents a pleasing appearance, and which will not produce any undesirable abrupt margins adjacent the portion thereof carrying the comb.

To these and other ends, the invention consists in the construction, arrangement and combination of parts described herein-after and pointed out in the claims.

One embodiment of the invention is represented by way of example in the accompanying drawings, wherein:

Figure 1, represents a plan view of the brush carrying portion of the body, or brush section,

Fig. 2, is a plan view of the mirror carrying portion of the body, or mirror section,

Fig. 3, is a plan view of the sections of the body opened up to clearly show the article receiving compartment formed therein,

Fig. 4, is an edge view of the toilet article, and

Fig. 5, is a transverse sectional view showing the manner of assembling the various parts.

In the drawings wherein like characters of reference indicate like or similar parts throughout the several views:

(A) designates the body or casing of the toilet article in its entirety, which is formed with complementary hingedly connected sections 1 and 2. The sections 1 and 2 have substantially oval body portions 3 and elongated handle members 4. Carried by the handle members 4 is a suitable fastener 5 for maintaining the sections in a closed position when so desired. Attention is called to the fact that the sections 1 and 2 resemble in configuration, when closed, a brush back of conventional type, and for the sake of clarity they will hereinafter be termed the brush section and the comb section respectively.

The brush section 1 is formed with a broadly beveled straight edge 6; the bevel extending inwardly adjacent to the center of the section, as shown in Fig. 1, where a brush 7 is mounted. The brush 7 is preferably elongated and extends lengthwise of the section as illustrated. The inner face of the section 1 is cut away as at 8 to form a chamber or receptacle within which are carried a powder-puff, hair pins, scissors and the like, generally designated by 9. It is to be noted that the peculiar arrangement of the brush with respect to the beveled edge 6 and body portion affords great facility in using the same for its usual purposes.

The comb section 2, while resembling the brush section 1 in general configuration, is of much less thickness (see Fig. 4) and is designed to serve as a cover for the receptacle 8 formed in the brush section. The comb section 2 is formed with a straight edge 10 registering with the beveled edge 6 of the brush section and either mounted upon or formed integrally upon the straight edge 10 is a comb 11. Attention is here called to the fact that the beveled edge 6 is formed with such a gradual slope that all abrupt margins adjacent the comb are eliminated, so that the same may be used with facility. Upon the outer face of the comb section 2 is mounted a suitable mirror 12, and the meeting edges of both the brush section and the comb section are beveled to form a compact and useful article which is very pleasing in appearance.

In operation the cut-away portion or

chamber 8 affords a suitable receptacle for scissors, hair pins and the like; and the brush 7, comb 11 and mirror 12 can be used without inconvenience and to their greatest advantage for their usual purposes. Furthermore, the invention in its entirety forms a complete toilet article which may be packed and transported with ease and to the great convenience of the traveler.

10 While in the foregoing, there has been illustrated in the drawings and described in the specification such combination and arrangement of elements as constitute the preferred embodiment of the invention, it is nevertheless desired to emphasize the fact that interpretation of the invention should only be conclusive when made in the light of the subjoined claims.

Having described the invention and its 20 objects with such attention to detail as will thoroughly acquaint one skilled in the art with its construction and advantages, I claim—

1. A toilet article of the type described 25 comprising a sectional body portion, said sections normally disposed in superposed registering position with respect to each other, registering straight edges formed on the sections, a comb mounted on one of the 30 straight edges, and the other straight edge being beveled to form a gradual rise from the comb.

2. A toilet article of the type described comprising a sectional substantially hollow 35 body portion, a comb carried by the body portion, and the sections of the body portion beveled to form a gradual rise from the comb.

3. A toilet article of the type described 40 comprising a body portion formed of hinged- edly connected, superposed sections, one of the sections being cut-away to form a compartment and provided on one of its edges with a broad bevel, the other section forming 45 a closure for the compartment, and a

comb carried by the last named section for the purpose set forth.

4. A toilet article of the type described comprising a body portion formed of hinged- edly connected superposed sections, a brush 50 carried by one of the sections, a comb carried by the other section, and the first named section provided with a broad bevel from the brush to the comb whereby to maintain the normal functions of each. 55

5. The combination in a toilet article, having a body portion formed of sections providing a normally closed compartment, of a brush carried by one of the sections, a mirror carried by the other of the sections, 60 and a comb mounted on the edge of one of the sections between the brush and the mirror and directed outwardly from the body portion at a relatively great distance from the brush and mirror for the purpose set 65 forth.

6. A toilet article of the type described comprising a body portion formed of hinged- edly connected sections, an elongated brush 70 carried by one section and disposed adjacent one of the side edges of the body portion, a comb carried by the other section and disposed upon the edge of the section on the side of the body portion opposite the brush, and the first named section provided with a broad bevel from the brush to the comb whereby to maintain the normal 75 functions of each.

7. A toilet article of the type described comprising a sectional body portion, a comb 80 mounted on one of the edges of the body portion, a brush mounted adjacent the edge of the body portion opposite the comb, and the last named section being beveled from the comb to the brush for the purpose set 85 forth.

In testimony whereof, I affix my signature hereto.

VAN JENNINGS AULT.
